GRAVE MARKER

Richard J. Lasher, Wethersfield, Conn., assignor
to The Rose Hill Cemetery Co., Rocky Hill,
Conn., a corporation of Connecticut

Application November 16, 1951, Serial No. 17,443

Term of patent 14 years

(Cl. D79—2)

To all whom it may concern:

Be it known that I Richard J. Lasher, a citizen of the United States, residing at Wethersfield, in the county of Hartford, State of Connecticut, have invented a new, original, and ornamental Design for a Grave Marker, of which the following is a specification, reference being had to the accompanying drawing, forming a part hereof.

In the drawing:

Fig. 1 is a plan view of a grave marker, embodying my new design;

Fig. 2 is a front edge view; and

Fig. 3 is a cross-sectional view along the line 3—3 of Fig. 2.

The characteristic features of the design reside in the solid line portion.

I claim:

The ornamental design for a grave marker, as shown and described.

RICHARD J. LASHER.
